UNITED STATES PATENT OFFICE.

HIRAM A. HAWKINS, OF CHICAGO, ILLINOIS.

CORN-SHELLER.

SPECIFICATION forming part of Letters Patent No. 252,373, dated January 17, 1882

Application filed May 26, 1881. (No model.)

To all whom it may concern:

Be it known that I, HIRAM A. HAWKINS, of Chicago, in the county of Cook and State of Illinois, have invented a new and useful Corn-Shell, of which the following is a specification.

My invention relates to improvements in corn shellers in which are cylinders and cases made in sections or staves, and automatically adjustable; and the objects of my invention are, first, to provide a cylinder and case both made in staves or sections, the sections or staves being removable; second, to furnish an attachment or spring, in connection with the cylinder and case, so that they will automatically adjust themselves; and, third, to furnish a corn-sheller which will require less power than those now in use, and be cheap, light, and durable. I attain these objects by the mechanism as illustrated in the accompanying drawings, in which—

Figure 1 is a side view of my new corn-sheller. Fig. 2 is a sectional view on the line $x x$ of Fig. 1. Fig. 3 is a top view of the bottom plate upon which rest the case and cylinder, showing their plate-connections, and with each other. Fig. 4 is the inside of one of the staves or sections of the case, showing position of teeth. Fig. 5 is an edge view of the same. Fig. 6 is an outside view of one of the staves or sections of cylinder, showing position of teeth and shape of edges forming the openings between the staves for the discharge of the shelled corn. Fig. 7 is an edge view of the same. Fig. 8 is a bottom view of the top of the cylinder, showing the sockets for the reception of the ends of the staves, and showing groove. Fig. 9 is a view showing the spring attachment for automatically adjusting the staves of the case.

Similar letters refer to similar parts throughout the several views.

A is a case of a corn-sheller. It is made of staves or sections $a a$, the staves being removable. The tops of the staves $a a$ rest in a groove in the lower edge of hopper B, and the bottoms of staves on projection F, as shown in Fig. 9.

B is an ordinary hopper, provided with a groove for reception of top of staves $a a$. 50

C is a cylinder, made of removable staves or sections $b b$.

$a a$ are staves forming case A, and are made in the shape as shown in Figs. 4 and 5. They are provided with teeth or projections $h h$, 55 which teeth are in the position as shown, having projection V.

$b b$ are staves forming the cylinder C, and made in the shape as shown in Fig. 6, so that holes w will be in the cylinder for the passage 60 of the corn. $b b$ have teeth e on the outside for separating the corn from the cob. The top ends of $b b$ rest in sockets $e e$ of head of cylinder, the bottom end resting in a groove on spider W. 65

D is the head of the cylinder. It is keyed upon the shaft K. It is hollowed out upon its under side, and has a groove, d, with sockets e, for reception of the end of staves $b b$.

E is a plate, made of iron, having projections 70 F and n, and serves as a support for the cylinder and case.

F is a projection on the upper face of E, having head or shank f, all cast in one piece, and also solidly cast with plate E. F is cast 75 in shape as shown in Fig. 9. f has a threaded hole, r, through which the tension-screw R passes.

R is a tension-screw.

T is a washer, loosely attached to end of R, 80 and having shank t for spring S, all as shown in Fig. 9.

S is a spring, and is for the purpose of allowing the staves to automatically adjust themselves. At one end it has a bearing on t, and 85 at the other on projection V of stave a. Each stave a has the arrangement as shown in Fig. 9.

H is an iron frame for the support of the corn-sheller.

K is a revolving shaft passing through the 90 center of the cylinder C. Its top end passes through bearings in frame H, and has a pulley attached, and its lower end rests in a center-lift trampot supported by lever M, the lever M being supported by rods N N, running up 95 through plate E and having hand-wheels P.

Underneath the hand-wheels P are coiled springs g, which have a bearing on plate E and wheel P, as shown in Fig. 1, and are for the purpose of automatically adjusting the cylinder.

5 L is an iron bridge-tree or shaft-support.

W is an iron spider, having grooves to receive lower end of staves b b, and is held in position by rods k k.

10 k k are iron rods, which pass through the spider W and cylinder-head D, as shown in Fig. 2, being secured at both ends by nuts. These rods k k keep spider W and staves b b in position, and by slackening the nuts the staves may be removed when desired.

15 n n are projections on E for separating the ends of staves a a and preventing the staves passing inwardly or sidewise, they being made inclined, with a hook, as shown in Fig. 9, and 20 are cast with E.

25 w w are holes in the cylinder, which are formed when the staves b b are put together and the cylinder complete, and are for the purpose of a discharge of shelled corn through the spider W.

All the several parts of my invention are made of iron; but they may be made of any material suitable for the purpose, and are arranged as shown.

30 The manner of operation is as follows: The machine is put in motion by power attached to shaft K, causing the shaft and cylinder to revolve. The corn is put into the hopper B, and it passes down into the machine between

the cylinder C and the case A and between the 35 teeth c and h, and the corn will be forced from the cob. The separated corn will pass down into a reservoir for the reception of the same. Some of the corn will pass through the holes w and spider W into the reservoir, the holes w 40 acting as a relief for the general delivery. In the event a large cob passes down, the staves of the case will adjust themselves so as to accommodate a large or small cob, automatically moving forward or backward; and in the case 45 of a very heavy strain the cylinder will yield downwardly, thereby enlarging the general delivery, obviating the danger of breaking; and, if desired, the cylinder and case may be separated into their several parts or sections 50 in a few moments.

What I claim as new and original, and desire to secure by Letters Patent, is—

1. The combination, in a corn-sheller, of the plate E, having projections F and n, with the 55 case A and rods N, substantially as described and shown.

2. The combination, in a corn-sheller, of the hopper B, cylinder C, case A, grooved spider W, and plate E, having projections F and n, 60 the said case and cylinder being formed in sections and provided with devices for rendering them automatically adjustable, substantially as shown and described.

HIRAM A. HAWKINS.
